UNITED STATES PATENT OFFICE.

BENJAMIN GWATKIN AND VICTOR E. RANDALL, OF BATTLE CREEK, AND WILSON E. WHITE, OF DETROIT, MICHIGAN.

EMERGENCY TRAIN-STOPPING MECHANISM.

1,355,329.

Specification of Letters Patent. Patented Oct. 12, 1920.

Application filed January 9, 1917. Serial No. 141,484.

To all whom it may concern:

Be it known that we, BENJAMIN GWATKIN and VICTOR E. RANDALL, citizens of the United States, residing at Battle Creek, in the county of Calhoun and State of Michigan, and WILSON E. WHITE, of Detroit, in the county of Wayne and State of Michigan, have invented certain new and useful Improvements in Emergency Train-Stop- ping Mechanism, of which the following is a specification.

This invention relates to emergency train stopping mechanism by which a moving train may be brought to a standstill through external means wholly outside of the action of an engineer, fireman or train operative.

If through illness, accident or oversight of an engineer, an order to slacken or stop a train under his charge has been violated, serious consequences and oftentimes great loss of life and destruction of property has resulted. The present invention has chief among its objects the avoidance of such catastrophes, and to provide means whereby

25 by a train may be brought to a standstill without injury to the rolling stock and wholly independent of any action at the hands of a trainman. Other objects are, to provide a mechanism for the purpose where- 30 by the brakes to both the engine and train may be applied through devices on the engine that will cut into the air-brake system and throttle the engine at one and the same time by means of local external apparatus

35 either to the outside or between the rails over which the train passes; whereby the throttle valve mechanism may be operated without molesting the engineer's hand lever; whereby the mechanism will be comparatively simple and compact, economical to manufacture, durable and positive in operation, and capable of being installed on engines not especially designed for the purpose. With these and other objects in view,

45 the invention consists in certain arrangement and combination of parts, as will be hereinafter more fully set forth and described.

In the drawings forming a part of the specification, Figure 1 is a rear view of a locomotive with our improved train stopping mechanism and a stationary lever operated stop set to intercept and operate said mechanism, the engine being represented as moving in a forward direction.

Fig. 2 is a broken side view of an engine with the train stopping mechanism, and a stationary lever operated stop set to intercept and operate said mechanism, the engine being represented as moving in a forward direction.

Fig. 3 is a detail front elevation of the automatic mechanism for throttling the steam and cutting into the train air brake pipe service.

Fig. 4 is a side elevation of the same.

Fig. 5 is a plan view of Fig. 3 on the dotted line α' .

In the drawings, like marks of reference refer to corresponding parts in the different views in which A, represents a locomotive; B, its cab; C, the roadbed, including its cross ties and rails; D, a stationary lever operated stop fitted between the ties of the road bed, the same being set to intercept the crank E of the mechanism attached to the locomotive for operating the train stopping mechanism proper.

The stop D, as herein shown, may be controlled from a source at a distance from which it is operated; or in combination with a semaphore, switch or other device, and, again, it might be simply a portable stop such as is set forth and described in the application for Letters Patent #92862 of April 2, 1916.

F, represents the customary engineer's valve through which air is supplied in the usual manner from storage tank, as G, from a pump H, and 1, 1, represent the air train brake pipes leading from the engine to the train for operating the brake service of said train.

Fitted to the locomotive within the cab, the train-stopping mechanism I is fitted by means of bolts 2 screw-threaded within the locomotive boiler and positioned above and slightly to one side of the fire box door 3. This mechanism has a cylinder 4 to which steam is admitted from the locomotive boiler at or near the lower extremity thereof through a pipe 5 leading from the steam dome of the locomotive. Within the cylinder a suitable piston is fitted, from which a piston rod 6 extends in an upward direction, the same being moved by the admission of steam through the pipe 5, as will be hereinafter more fully described.

Pivoted to one side of the piston rod 6 on an extension 7 of the bracket of the

mechanism and crossing said rod in a horizontal direction, is the engineer's throttle operating lever 8. This lever is controlled with a latch and quadrant by the engineer 5 in the ordinary manner for operating an engine under normal conditions, the latch and quadrant not being shown. At a point 10 on the lever 8 between its pivotal connection 11 and the rod 6, the throttle valve rod 9 is attached by means of a forked-topped pin 10.

The pin 11 on which the throttle lever 8 hinges has a forked lower extremity 11' between the prongs of which a goose-neck lever 12 is pivoted on a pin Z, the upper curved extremity of which overhangs the forked pin 10 to which it is connected by a link 13, an extension 14 having a friction roller 15 at its extremity forming a part 15 below the goose-neck portion aforesaid.

The piston rod 6 has a transversely-disposed race 16 upon which the roller 15 is adapted to rest, the roller in connection with a guide finger 17 extending below the race 20, preventing the lever 12 from vertical displacement with said race, yet permitting the throttle lever 8 and arm 12 free lateral movement with respect to the piston rod 6.

The throttle valve rod 9 to one side of its 30 pivotal connection with the lever 8 forms a yoke 18. This yoke straddles a flattened guide 19 fitted to or forming a part of the piston rod 6, the guide having a tapering edge 21 slanting from its top downwardly 35 toward the locomotive boiler, thence terminating vertically. The tapering surface of the guide 21 is such that its contact with the yoke 18 will move the throttle rod and close the valve of an engine when the piston rod 40 6 is moved sufficiently upward.

A stem 22 having a longitudinal slot 23 forms a terminal of the piston rod 6. This 45 stem operates through a chamber 25 in a bracket J, from which chamber one or more tubes connect with the train air brake pipes 1. The upper end of the chamber 25 is screw-threaded and fitted with a correspondingly screw-threaded air escape plug 26, vertically through which said rod 22 operates, 50 air being prevented from escaping from the chamber 25 about the rod both above and below the bracket by means of gasket packings 27 and 28, respectively, when the rod 22 is in normal position as shown, but capable of permitting air to escape through the 55 vent 29 in the plug 26 when the rod 22 is elevated to permit the slot 23' to register with said vent.

Suspended from the engine frame by 60 brackets 30, a rock-shaft 31 is fitted. This shaft carries a double crank E, the lower arm of which hangs below the rock-shaft 31, and it is arranged to engage the upturned arm 32 of the stop D when the latter is elevated, whether the engine is going forward 65

or backward. The upper portion of the crank E is aligned with its lower arm, and it is connected with a rock-arm 33 adapted to operate a cut-out valve 34 between the cylinder 4 and pipe 5 by means of a connecting 70 rod 35.

The arrangement of the crank E, connecting rod 35, rock-arm 33 and its valves 34 intercepting the passage between the cylinder 4 and pipe 5, is such that when the stop 75 arm 32 is elevated, the crank E will operate the valve 34 and provide a passage permitting steam to flow from the engine boiler into the cylinder 4 and cause its piston to move upwardly. As will be obvious, an upward movement of the piston 6 and its race 80 16 will by means of the friction roller 15 and its arm 14 cause the goose-neck arm 12 to swing upwardly on its pivot 11 and cause the link 13 to raise the throttle rod pin 10 85 and release the throttle rod from the engineer's lever 8.

The arrangement of the parts is such that immediately following the lifting of the pin 10 from the engineer's lever 8, the tapering-faced guide 21 will cause the throttle rod 9 to move inwardly and close the engine valve, and immediately upon closing the engine valve to stop the engine by cutting off the steam supply. The stem 22 of the piston 95 rod 6, will, through the aforesaid process, have raised sufficiently high within the apertured plug 26 to permit the slot 23' to register with the vent 29 in the plug 26 and permit the air in the train pipes 1, 1, to flow 100 through the lead pipes 23 and 24 and chamber 25, and escape by means of the slot 23' and the vent 29 when the stem 22 has been sufficiently elevated to register the aforesaid openings and cause the brakes on both the 105 engine and train to be set through means of a triple valve system in such manner as would be the case should a leak occur in the train service pipes and the train be brought to a standstill through the operation of the 110 mechanism as set forth.

To enable a train to proceed, the parts of necessity are restored to their former position, which can be readily accomplished by turning the crank E to its normal position, 115 (a process which ordinarily makes it necessary for the engineer or some train operative to dismount from the locomotive), after which the pin 10 may be passed through the valve rod and the engineer's lever 8. 120

It would be obvious that in lieu of employing steam to actuate the piston in the cylinder 4, compressed air would answer as well for the purpose, an object in employing the steam being to afford means for throttling an engine by means of its own motive force in the absence of compressed air, which is not available under every circumstance. The piston having been operated either through the means of steam or compressed 130

air, as aforesaid, may be restored to its normal position by releasing compression in said cylinder through the medium of an escape pipe *x* having a vent sufficiently small to permit the pressure in the cylinder to actuate the piston and afterward to be gradually released through said pipe, or the pipe may be under the control of a pet cock.

We are aware that certain details of construction could be resorted to without departing from or sacrificing the spirit of our invention, and we reserve the right to arrange and construct the various elements in any manner compatible with the intent and scope of our invention.

Having, therefore, described our invention, what we claim as new and desire to secure by Letters Patent, is:

1. In a device of the class set forth, the combination with a locomotive and a stopping device fitted near the rails over which the locomotive passes, a rock-arm fitted to the locomotive in alinement and arranged to engage said stopping device, a cylinder mounted on said locomotive, a piston rod operative from within said cylinder, a valve to control the motive force that actuates said piston rod, means connecting said rock-arm with said valve whereby said valve may be operated from said rock-arm when in engagement with said stopping device, means for disconnecting the throttle valve lever from the throttle valve rod, and means for closing the throttle valve by an upward movement of said piston rod subsequent to means for disconnecting the throttle valve lever from the throttle valve rod.

2. In a device of the class set forth, the combination with the locomotive, a throttle valve and valve rod, the engineer's lever for operating the valve rod, the air brake system of said locomotive and a track device for engaging train stopping mechanism on said locomotive, of a cylinder mounted on said locomotive, a piston rod operative from within said cylinder, a valve to control the motive force for operating said piston rod from within said cylinder, means to actuate said valve by engaging said track device, means on said piston rod for disconnecting the engineer's lever from said throttle valve rod, and means on said piston rod for moving said throttle valve lever to close said throttle valve by an upward stroke movement of said piston rod subsequent to disconnecting said throttle valve lever from said throttle valve rod, and means for operating said air brake system by said piston rod subsequent to said means for disconnecting the engineer's lever from said throttle valve rod.

3. In a device of the class set forth, the combination with a locomotive, its throttle valve and throttle valve rod, the engineer's lever pivoted to said rod for operating said

valve, the air brake system of the locomotive, and a track device for engaging train stopping mechanism on said locomotive, of a cylinder fitted to said locomotive, a piston rod operative from within said cylinder, means to actuate said piston rod wholly outside of any action of a locomotive attendant, said piston rod extending from said cylinder to one side of said throttle valve rod, an arm pivotally mounted to one side of said throttle valve rod and extending above the pivotal connection with said engineer's lever, a link connecting said arm with said pivotal connection, means for elevating said arm and releasing said pivotal pin by an upward movement of said piston rod, and means to push in said valve rod and close said valve subsequent to releasing said pivotal pin, the same to be automatically accomplished by the upward movement of said piston rod.

4. In a device of the class set forth, the combination with the locomotive, a throttle valve and valve rod, the engineer's lever for operating the valve rod, the air brake system of said locomotive and a track device for engaging train stopping mechanism on said locomotive, of a cylinder mounted on said locomotive, a piston rod operative from within said cylinder, means to actuate said valve by engaging said track device, an arm pivotally suspended from the pivotal pin of said engineer's lever, a link suspended from the opposite end of said arm and pivotally connected with the pin connecting the throttle valve with the engineer's lever, means for elevating said arm and releasing the pin connecting the throttle valve rod by an upward movement of said piston rod, and means to push in said valve rod and close said valve subsequent to releasing the pin connecting the throttle valve rod, as and for the purpose set forth.

5. In a device of the class set forth, the combination with the locomotive, a throttle valve and valve rod, the engineer's lever for operating the valve rod, the air brake system of said locomotive and a track device for engaging train stopping mechanism on said locomotive, of a cylinder mounted on said locomotive, a motive induction pipe leading to said cylinder, a valve controlling the motive element through said pipe to said cylinder, a rock arm extending from said valve, a rock shaft journaled to said locomotive, a rock arm extending from said shaft adapted to engage said track device, a connecting rod connecting the rock arm extending from said valve with the rock arm of said rock shaft whereby when said track device is engaged by the one said valve will be opened, a piston operative from within said cylinder by said motive element, an arm pivotally suspended from the pivotal pin of said engineer's lever, a link suspended from the opposite end of said arm

4
 and pivotally connected with the pin connecting the throttle valve rod with said engineer's lever, a transverse race on said piston, means extending from said arm engaging said race whereby said arm may be moved laterally along said race by the operation of said engineer's lever, said race adapted to lift said arm by an upward movement of said piston and lift said pin connecting said throttle valve rod with said engineer's lever, means to close said throttle valve by an upward movement of said piston subsequent to disengaging the pin connecting said throttle valve rod from said engineer's lever, and means to operate said air brake system subsequent to closing said throttle valve, for the purpose set forth.

6. In a device of the class set forth, the combination with the air brake system of a locomotive, the engineer's lever, the throttle valve rod and throttle valve of a locomotive, of the cylinder mounted on said locomotive, a piston rod operative from within said cylinder, a motive conducting pipe leading to said cylinder, a valve for controlling the motive element through said pipe to said cylinder, means for operating said valve wholly independent of the initiative of a locomotive or other attendant, means to disconnect said engineer's lever from said throttle valve rod by an upward movement of said piston rod antecedent to means for closing said throttle valve by an upward movement of said piston rod, and means to operate said air brake system subsequent to closing said throttle valve, for the purpose set forth.

7. In a device of the class set forth, the combination with the air brake system of a locomotive, the engineer's lever, throttle

valve rod and the throttle valve, of a cylinder, a piston rod operative from said cylinder, means to operate said piston rod through a medium in said cylinder, said piston rod having a guide with a vertical tapering face, said valve rod having a yoke striding said guide, a yoke-pin to which said engineer's lever is hinged, a goose-neck lever mounted in said yoke pin, a link connecting said goose-neck lever with a pin connecting said engineer's lever with said throttle valve rod, a horizontal race extending from said piston rod, a roller and a finger on said goose-neck lever engaging said horizontal race whereby said race will permit said goose-neck lever to have lateral sway in the operation of said engineer's lever with said throttle, but will lift the pin connecting said engineer's lever with said throttle valve rod by an upward movement of said piston rod, said tapering guide adapted to push in on said yoke striding said guide and close said throttle valve subsequent to lifting said goose-neck lever and said link and disengaging said pin connecting said engineer's lever with said throttle valve rod, and means to operate said air brake system of said locomotive subsequent to closing said throttle valve, substantially as and for the purpose set forth.
